CLAIM

We claim the ornamental design for an electric oven, as shown and described.

DESCRIPTION

FIG. 1 is a front perspective view of an electric oven showing our new design according to a first embodiment; FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion in FIG. 1;

FIG. 9 is a front perspective view of an electric oven showing our new design according to a second embodiment; FIG. 10 is a front view thereof;

FIG. 11 is a rear view thereof;

FIG. 12 is a left-side view thereof;

FIG. 13 is a right-side view thereof;

FIG. 14 is a top view thereof;

FIG. 15 is a bottom view thereof; and,

FIG. 16 is an enlarged view of the encircled portion in FIG. 9.

The broken lines in the figures depict portions of the electric oven that form no part of the claimed design.

(Continued)

The dot-dash broken lines encircling portions of the claimed design that are illustrated in enlargements form no part of the claimed design.
